UNITED STATES PATENT OFFICE.

LEVI STOKES AND THOMAS M. VICKERS, OF RICHMOND, CALIFORNIA.

LIQUID-FUEL BURNER.

955,715.

Specification of Letters Patent. Patented Apr. 19, 1910.

Application filed September 18, 1909. Serial No. 518,310.

To all whom it may concern:

Be it known that we, LEVI STOKES and THOMAS M. VICKERS, citizens of the United States, residing at Richmond, in the county 5 of Contra Costa, State of California, have invented a new and useful Liquid-Fuel Burner, of which the following is a specification.

This invention relates to liquid fuel burners of that type known as injector burners which spray or inject atomized liquid fuel into the combustion chamber of the furnace, the atomizing fluid being steam, and the object of the invention is to effect a more 10 thorough mixture of the fuel and steam, and also to heat the fuel to a very high degree 15 before it is sprayed into the combustion chamber.

Another object is to provide a burner structure which produces a bright flame, thus eliminating black smoke and preventing the escape of gas from the stack.

Another object is to provide a burner in which the dropping of oil after the supply 25 has been shut off, is prevented.

With these objects in view, the invention consists in the novel construction and arrangement of parts to be hereinafter described and claimed, reference being had to 30 the drawing hereto annexed, in which,

Figure 1 is a longitudinal sectional view of the burner; Fig. 2 is an elevational view of one of the nozzles; Fig. 3 is a longitudinal section of the burner tip; taken at right 35 angles to the plane on which Fig. 1 was taken.

In the drawings, 5 denotes the body of the burner comprising a cylindrical shell having intermediate its ends an inlet 6 for the oil 40 or other liquid fuel, and at one end an inlet 7 for the steam, the last mentioned inlet leading to a nozzle 8 located in the bore of the shell adjacent to the inlet. To the opposite end of the burner body is fitted a tip 9 45 which is rectangular in cross section, and has its discharge end substantially semi-circular, with a slit 10 in said end from which the atomized fuel issues. The end of the tip which is connected to the burner 50 body has a reduced and cylindrical portion 11 which is externally screw threaded to screw into the burner body as shown in Fig. 1. The bore of the reduced portion 11 of the tip 9 is also reduced, and a portion of 55 said bore is screw threaded into which screws a nozzle 12 which extends at its discharge

end into the main bore of the tip. The opposite end of the nozzle has a shoulder 13 which abuts against the end of the part 11, and to the rear of this shoulder is an extension 14 which is externally screw threaded for connection to an intermediate nozzle which is indicated at 15.

The inlet end of the nozzle 15 is located directly in front of the discharge end of the nozzle 8, and its discharge end is located behind the inlet end of the nozzle 12, these three nozzles being located close together, and in axial alinement. The inlet end of the nozzle 15 is enlarged and has side openings 16, and this end of the nozzle is located close to the inlet 6. The oil or other liquid fuel enters the nozzle 15 through the openings 16 and also through its inlet end, the interior diameter of which is greater than 75 the diameter of the nozzle 8, which leaves a space between said parts through which the oil enters the nozzle 15.

Adjacent to its discharge end, the nozzle 15 has a series of outwardly and forwardly 80 presented fingers 17 terminating in screw threaded portions 18 engageable with the extension 14, whereby the nozzle 15 is connected to the nozzle 12.

In the bore of the tip 9, intermediate its 85 ends, is a baffle 19 which is located so as to extend behind the slit 10.

In operation, steam enters the burner through the inlet 7, and passes successively through the nozzles 8, 15 and 12, which produces a vacuum in the bore of the burner body 5, and causes the oil to enter the nozzle 15 through the openings 16 as well as its inlet end, where it is taken up by the steam and carried with the same into the tip 9. 95 Here the oil and steam are deflected by the baffle 19, and prevented from being driven directly through the slit 10, whereby a thorough mixture of the oil and steam is effected, and the oil is heated to a very high degree before leaving the tip. The slit 10 is very small which results in the accumulation of considerable pressure in the tip, and the oil is thoroughly atomized when leaving the same. There is also considerable 100 gas generated in the tip which produces a bright flame, and eliminates black smoke, and the escape of gas from the stack. The only communication between the burner body and the tip is through the nozzle 12, 110 which prevents the oil and steam from being forced back into the burner body.

The slit 10 is located near the top of the tip, so as to prevent dropping of oil after it has been shut off. This not only saves the loss of oil, but eliminates the danger of fire.

The burner is simple in structure and the parts can be readily assembled, and also taken apart for cleaning or repairs.

What is claimed is:—

10 In a liquid fuel burner, a burner body having a side fuel inlet, and a steam inlet at one end, a tip on the opposite end of the burner body, and having its inlet end contracted and internally screw threaded, a
15 nozzle screwed into said contracted end, and projecting at its discharge end into the bore of the tip, the opposite end of the nozzle having a screw threaded extension, a nozzle in the burner body in communication

with the steam inlet, and an intermediate 20 nozzle having its bore in communication with the bore of the burner body, and arms projecting from said intermediate nozzle, and having screw threaded ends engageable with the aforesaid threaded extension.

In testimony that we claim the foregoing as our own, we have hereto affixed our signatures in the presence of two witnesses.

LEVI STOKES.

THOMAS M. VICKERS.
